(57) **CLAIM**

The ornamental design for an “unmanned aircraft”, as shown and described.

DESCRIPTION

The present application is related to U.S. Patent application Ser. No. 16/542,542 filed on Aug. 16, 2019 entitled “Unmanned Aircraft having Reduced Acoustic Signatures” (now U.S. Pat. No. 11,597,514), the entire contents of which are expressly incorporated hereinto by reference.

FIG. 1 is a left front perspective view from above showing our new and original design for an unmanned aircraft;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof; and,

FIG. 8 is a left rear perspective view thereof from above. The dashed lines shown in the drawings depict portions of the unmanned aircraft that form no part of the claimed design.

1 Claim, 7 Drawing Sheets
